UNITED STATES PATENT OFFICE.

GASTON GALY, OF BOIS COLOMBES, FRANCE.

MATCH.

No. 914,264.

Specification of Letters Patent. Patented March 2, 1909.

Application filed March 23, 1908. Serial No. 423,334.

To all whom it may concern:

Be it known that I, GASTON GALY, a citizen of the Republic of France, residing at Bois Colombes, France, have invented certain new and useful Improvements in Matches, of which the following is a specification.

The present invention has reference to improvements in matches, and relates more especially to a substitute for the well known wooden match, and the object of the invention is to provide such a substitute, which will more easily ignite, more readily keep burning, will take up less space, and is considerably lighter than the ordinary wooden match. As a further advantage, the improved match can be used without any special friction surface, such as the surface of the match safe, house wall or other suitable surface, inasmuch as the combustible composition as well as the friction surface are both provided on each match, and the matches readily ignite upon being withdrawn off the package or from the box containing them.

In order to make the invention more readily understood, I will now describe it with reference to the accompanying drawings, in which—

Figure 1 shows a plan view of one form of my improved match, Fig. 1^a is an edge view thereof, Fig. 2 is an edge view of a number of such matches or ignition strips, overlapping one another to form a bundle, Fig. 3 is a longitudinal section through a box containing a bundle of matches. Fig. 3^a is a side view of the receptacle. Fig. 4 is a cross section through a modification.

The strip *a* of suitable material, for instance tough paper or the like, is impregnated with paraffin or some other flame aiding medium and carries at one end the combustible composition *b* and at the other end the friction mass *c*. If now the strip is bent back upon itself and the end *b* is rubbed over the end *c*, the composition will readily ignite and the match is lighted. To do this automatically in a convenient manner, a number of such strips are folded into one another, as illustrated in Fig. 2, and a package or bundle is formed.

In this bundle, the end *c* of each strip forms the friction surface for the end *b* of the preceding strip. If now the strip 1, at its free end *d* is being pulled out, its composition end *b* will be ignited by coming into contact with

the friction end *c* of the strip 2, and so on with each following match 3, 4, 5, 6. In order to insure the ignition, the bundle should be compressed in the direction of the arrows, which can be done either by finger pressure or mechanically, as for instance in a suitably shaped case *m*, by means of springs *e* acting on a false bottom *n*. The strip, just before issuing from this box, passes between guide-springs *f*. The friction between each two strips is great enough to also pull the end of the succeeding strip through the opening *o* in the cover of the box every time a match is being pulled out, similar to the operation of the well known toilet paper dispensing device.

In the modification shown in Fig. 4, the combustible mixture and the friction mass are provided on separate strips, and the strips *h* containing the friction mass are clamped in suitable manner at one end and held compressed at the other end by means of a sleeve *k* or the like, and the strips *i* with the composition *b* are interposed between each two strips.

For obtaining special light effects with these matches, the latter may be coated with Bengal fire composition or the like in any desired color combinations.

What I claim and desire to secure by Letters Patent is:

1. A plurality of superposed flexible match strips, each provided on the same side and at opposite ends respectively with a combustible composition and a friction surface, each strip being bent into U-shape and having one of its legs between the legs of an adjacent similarly bent strip.

2. A plurality of superposed flexible match strips, each provided on the same side and at opposite ends respectively with a combustible composition and a friction surface, each strip being bent into U-shape, with the composition and friction surface on the inside, the lower leg of the upper strip and the upper leg of the third strip being inclosed between the leg of the second strip, substantially as described.

In testimony whereof I affix my signature in presence of two witnesses.

GASTON GALY.
